CAN LOADING MACHINE

William A. Steenberg and Donald Gray, San Leandro, Calif., assignors to Western Corrugated, Inc., a corporation of California

Filed Sept. 3, 1965, Ser. No. 484,903

3 Claims. (Cl. 53—153)

ABSTRACT OF THE DISCLOSURE

A carton loading machine, the machine having a plurality of ramps for receiving a supply of cans and having a ram which is actuated parallel to the ramps, pushing the cans into an end opening carton. In accordance with a preferred embodiment, a dual action machine is provided so that either top opening cartons or end opening cartons can be employed. In the preferred embodiment, two rams are employed which can be selectively actuated, one of which can be moved against the chines of the cans to push them into a top opening carton and a second ram which moves parallel to the ramps to push against the sides of the cans, pushing the cans into an end opening carton.

This invention relates to a machine for loading cans or similar articles into corrugated or similar containers, and more particularly relates to a machine for loading cans into an end-opening container or to a machine which is adapted to load both top-opening and end-opening containers.

It has heretofore been the practice to provide corrugated containers for canned goods which open from the top, employed four flaps for forming the top closure. Recently, new containers have been devised which have a solid top and which load from the end employing four flaps to form the end closure. However since the end is considerably smaller than the top, that portion of the container which has overlapping elements is smaller and consequently, end-loading containers utilize less cardboard for a container of a given size, resulting in a considerable economy. Machines have long been known for satisfactorily loading canned goods into top-opening containers but not for loading end opening containers. Further, despite the economy of the end-opening container, not all customers will accept it so it is frequently necessary for a canner to provide for loading both top-loading and end-loading containers.

It is therefore an object of the present invention to provide a machine of improved design for loading end-opening containers.

Another object of this invention is to provide a machine which is adapted to load both end-opening and side-opening containers without modification, so that a canner can use the same machine to load end-opening or top-opening containers depending on the customers' desires.

Other objects will be apparent from the balance of the specification which follows.

In the drawings forming part of this application:

FIGURE 1 is a side view of a machine embodying the present invention.

FIGURE 2 is a perspective view of a corrugated carton which has been loaded with the machine shown in FIGURE 1.

FIGURE 3 is a top view of the machine shown in FIGURE 1.

FIGURE 4 is an end view of the machine shown in FIGURE 1.

FIGURE 5 is a section on the line 5—5 of FIGURE 1.

FIGURE 6 is a section on the line 6—6 of FIGURE 5.

2

FIGURE 7 is a view similar to FIGURE 6 showing the parts in another position.

The machine of the present invention includes many parts in common with conventional top-loading carton filling machines such as that described in Patent 2,107,170. Since such machines are well known to those skilled in the art, that portion of the machine of the present invention is described only briefly. Thus, the machine includes a framework 8 mounted on suitable legs 9, the framework supporting a plurality of supply ramps 11 which lead to a source of canned goods, not shown. The framework also supports a plurality of loading ramps 13 provided with stop elements 15, the operation being that canned goods as at 16 roll down the supply ramps 11 until the loading ramps 13 are filled, where the cans are held in place by means of the stop element 15. A motor 17 driving belt 19 through a suitable reduction gear assembly 21 actuates a cam 23. An operating arm 25 pivoted at 27 and being provided with a cam follower 29 actuates a pusher assembly, designated 31, and having a plurality of ram elements 33, the pusher assembly being mounted on guide rails 35. A spring 37 normally urges the cam follower 29 into contact with cam 23. Thus the cycle of operation is that the ramps 13 are first loaded with cans, a carton is held with its open end toward the machine, i.e., away from the observer in FIGURE 1, and the ram mechanism 31 is then actuated by the action of the cam and spring, causing the rams to engage the chines and push the cans into the carton, loading all of the cans simultaneously into the container. The loading ramps 13 then fill up for a repetition of the operation. The operation thus far described is well known to those skilled in the art and has therefore only been briefly described. Further, in FIGURE 1, the cam follower 29 is not shown in contact with cam 23 but rather, the arm 25 has been locked away from the machine, as would be done when the machine is used for filling end-loading cartons, i.e., the operation which forms the gist of the present invention.

In the basic type of machine used for top-loading cartons the ramps 13 and stops 15 can be rigidly affixed to the frame of the machine. In accordance with the present invention, the ramps 13 are mounted by pivots 38 and 39 on the front fixed support members 41 and read vertical slide members 43, respectively. Removable side guides 14 may be provided on ramps 13. The stop elements 15 are mounted on the front vertical slide members 42.

A pusher element generally designated 45 mounted on rollers 47 and 49 operating on rails 51 and 53 is provided with inwardly extending arms 55. The arms 55 are adapted to reciprocate above the ramps 13, i.e., between the two positions shown in FIGURES 6 and 7 of the drawings. A double-acting pneumatic cylinder 57 having a piston rod 59 attached to the pusher element 45 serves to actuate the pusher mechanism. Air is supplied to the cylinder through a solenoid valve 61 having an inlet port 63 leading to a source of compressed air, not shown.

For the actuation of the slides 42 and 43, an auxiliary cam 65 is mounted on the gear reduction mechanism 21. A cam follower 67 is attached to rod 69 and rod 69 is attached to a bell crank 71 which pivots on shaft 73. The bell crank actuates the slide 43 while the linkage 75 operating off of shaft 73 and pivoted at 76 actuates the slide 42 through link 78.

In order to actuate the pneumatic cylinder 57, a raised member 77 on cam 23 operates a microswitch 79 which is attached by suitable wiring 81 to the solenoid valve 61, and to a power source, not illustrated.

Projecting at the end of the loading machine is a hood 83 having an opening 85 of substantially the same size as the end opening of a box to be loaded. Mounted

within the hood and extending therefrom are flap members 87 and 89 which support the upper two rows of cans and which prevent the cans from jamming as they are being loaded into containers. Also mounted within the hood are a series of spring elements 91, the function of which is to press inwardly, retaining cans in position opposite the spring elements. Mounted adjacent to the hood is a table 93 for supporting a case to be filled while deflector elements 95 located at the sides, top and bottom of the hood serve to keep the flaps of a container being filled out of the way and to prevent the flaps from interfering with the filling process.

The operation of the device in filling an end-opening carton will now be described. In starting the operation, it is assumed that there is one row, i.e., six cans within the hood 83 which are retained in position by the spring elements 91. Cans will now roll down the supply ramps 11 until the loading ramps 13 are filled as is shown in FIGURES 1 and 6. It will be noted that in this position, the pusher elements 55 are down, out of the way, permitting cans to pass thereover so that in effect, the pusher elements 55 form a connecting link between the ramps 11 and 13. Also, the elements 15 have restrained the first rows of cans so that only the desired number of cans have filled the loading ramps 13. An operator has placed a box, as is shown in phantom at 96, so that its open end coincides with the opening 85. As the first stage of the operation, as is best seen in FIGURE 7, the movable support 43 for the loading ramps is lowered so that the ends of the ramps, as at 13-A in FIGURE 7, 25 form an effective barrier for the remainder of cans 16 on the supply ramps 11. Thus, additional cans are prevented from rolling onto the loading ramps and interfering with the operation. Simultaneously with the lowering of the elements 43, which results in the supply of cans being cut off, element 42 is simultaneously lowered so that the elements 15, instead of holding back the cans as is shown in FIGURE 6, now form a continuation of the ramps 13 bridging the gap between the ramps 13 and the elements 87, 89 and the floor of the hood 83. 30 At this time, the cam element 77 closes the microswitch 79, resulting in the actuation of the pneumatic cylinder 57 causing the pusher element 45 carrying the arms 55 to move to the left to the position shown in FIGURE 7. This results in the cans being pushed into the waiting 35 carton 96 including the cans which were originally held within the hood 83 and all of the cans held on the ramps 13 except the last row of cans which are now locked in the hood 83. Further movement of the cam 77 results in the retraction of the pneumatic cylinder 57 so that the 40 arms 55 return to their former position. shortly thereafter, elements 42 and 43 are raised, blocking the passage of additional cans into the hood and permitting a new supply of cans to fill the ramps 13. Thus, the parts are restored to the position shown in FIGURE 6 so the 45 machine is now in position for a repetition of the cycle.

In the embodiment of the machine illustrated, the loading ramps are three in number and each holds eight cans, making a total of 24 held on the loading ramps. Obviously, this is for purposes of illustration only, and 50 the device could be built to accommodate different sizes and numbers of cans. Also, although cans have been referred to in the specification, this is also for illustration purposes only, since the device could be used for the loading of other commodities in paperboard or similar containers, such as salt or cereals.

The slide element 45 has been shown as being pneumatically actuated while elements 42 and 43 have been shown as being mechanically actuated from the cam. Here again, this is only for purposes of illustration, and all the elements could be pneumatically, hydraulically, or mechanically actuated, or any combination of these.

We claim:

1. A machine for loading cans into cartons, comprising in combination:
  - (a) a plurality of ramps for receiving cans;
  - (b) means for filling said loading ramps with cans in side by side relationship;
  - (c) a first ram and means to move said first ram sideways across said ramps against the chines of the cans, pushing said cans off of said ramps and into a top-opening carton; and
  - (d) a second ram and means to move said second ram parallel to said ramps against the sides of the cans, pushing said cans off of said ramps and into an end-opening carton.
2. A loading machine for loading a plurality of cans or the like into an end-opening carton, comprising in combination:
  - (a) a plurality of ramps for receiving cans;
  - (b) loading means for loading cans on said ramps;
  - (c) locking means normally preventing said cans from passing beyond said ramps;
  - (d) blocking means extending above said ramps, said blocking means, preventing additional cans from moving onto the loading ramps;
  - (e) a ram and means to move the ram against said cans pushing said cans off of said ramps into an end-loading carton; and
  - (f) interlocking actuating means, said interlocking actuating means (1) moving said locking means out of the path of the cans (2) moving said blocking means into path of additional cans and (3) moving said ram against said cans.
3. A loading machine for loading a plurality of cans or the like into an end-loading carton, comprising in combination:
  - (a) a plurality of can supply ramps;
  - (b) a plurality of can loading ramps, said loading ramps having pivot mounting means;
  - (c) said loading ramps forming a continuation of said supply ramps when the former are in a first position, and said loading ramps being movable to a second position wherein the ends of the said loading ramps block passage of cans from said supply ramps to said loading ramps;
  - (d) a ram and actuating means to move said ram against the sides of cans on said loading ramp, pushing said cans into an end-loading carton; and
  - (e) actuating means for operating said loading ramps and said ram in synchronism.
